CLAIM

The ornamental design for a misting fan kit, as shown and described.

DESCRIPTION

FIG. 1 is a rear, left and top perspective view of a misting fan kit, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view thereof, shown in a position of use; and,

FIG. 9 is an enlarged detail view of portion 9 encircled in FIG. 8.

The broken lines shown in the drawings illustrate portions of the misting fan kit that form no part of the claimed design. The dot-dash broken lines depict the boundaries of the enlargements that form no part of the claimed design.
